United States Patent Office.

J. G. C. HORTON, OF GILLESPIE, ILLINOIS.

Letters Patent No. 80,957, dated August 11, 1868.

IMPROVEMENT IN WATER-ELEVATORS.

The Schedule referred to in these Letters Patent and making part of the same.

TO ALL WHOM IT MAY CONCERN:

Be it known that I, J. G. C. HORTON, of Gillespie, in the county of Macoupin, and State of Illinois, have made certain new and useful Improvements in Water-Drawers; and I do hereby declare that the following is a full and clear description thereof, reference being had to the accompanying drawings, and to the letters of reference marked thereon.

The object of this invention is to raise water from wells, without the use of any tubing or pump-log whatever, and by means of a cheap and simple arrangement of buckets coupled together in a continuous chain, and drawn up by passing over a revolving wheel at the top of the well.

The chief features of the invention of this apparatus relate, firstly, to the formation of the buckets themselves, and secondly, to the crab, sunken at the bottom of the well, for the purpose of tightening and guiding the chain of buckets.

To enable those skilled in the art to make and use my improved water-drawer, I will proceed to describe its construction and operation.

Figure 1 of the drawings is a sectional elevation of a well provided with the improved device for drawing water:

Figure 2 is a front elevation of the upper or actuating-wheel.

Figure 3 is an enlarged sectional elevation of the bucket.

The buckets A should be constructed of some non-corrosive metal, and have an inclined bottom, near the lower corner of which an aperture, *a*, will permit the water in the buckets to be discharged down into the well, and thus avoid freezing the water in the buckets in the winter-time.

The buckets A are to be connected together in a continuous line, by means of the short chains *a'*, which connect the bottom of one bucket with the top of the next. The chain of buckets thus completed, it will be drawn tightly around the two wheels C C', the wheel C being placed on top of the platform at the top of the well, and turned around on its axis by the operator, so as to set the buckets in motion when the water is to be raised. The wheel C' is to have its bearings in the metallic crab B, which is to be sunken at the bottom of the well.

The wheels C C' are formed of two annular rims, connected together by transverse rods *c*, which are placed at such distances apart as to allow the chains *a'* to fall on the said rods as the wheel is revolved, thereby avoiding injury to the buckets by bending them over the rods as they pass around the wheels.

The crab B constitutes one principal feature of this invention, and by its use this form of water-drawer may be introduced into any well without the necessity of a person descending into the well to adjust or arrange the bottom of the pump, as has to be done in putting down all kinds of tube or chain-pumps. This crab may be a semicircular trough, constructed of some non-corrosive sheet metal, and arranged to furnish bearings for the lower wheel C', which will set down into the said trough. This crab will have short legs *b* at its bottom, which will settle down into the ground, at the bottom of the well, and hold the device firmly in place, thus furnishing a substantial and firm footing for the bottom end of the "drawer," without necessitating the descent of a person into the well for that purpose, as the chain of buckets may be placed around the lower wheel, and the whole apparatus lowered down into the well in that manner.

There are numerous perforations, *b'*, in the sides of the trough part of the crab, for the admission of the water to the buckets.

The curb D, which covers the well, has an inclined floor, *d*, on to which the buckets empty the water, as they turn over the upper wheel, and from this inclined floor the water is discharged through the spout *d'*.

A gate, *d''*, may be used to close the aperture to the spout, when the weather is so cold as to freeze inside of the curbing.

An aperture, *d'*, in the floor *d*, near its lower side, will permit the water on the floor, after the gate *d''* is shut down, to drain back into the well.

Having described my invention, what I claim, is—

1. The endless chain of buckets A a', and the stationary crab B, when combined and arranged as described, and for the purpose set forth.
2. The crab B, when provided with short legs b and side apertures b', and otherwise constructed and arranged as described and shown.

In testimony of which invention, I hereunto set my hand in presence of—
